UNITED STATES PATENT OFFICE.

ISAAC S. PURCELL, OF CHICAGO, ILLINOIS, ASSIGNOR TO TENTOBED COMPANY, OF CHICAGO, ILLINOIS, A CORPORATION OF ILLINOIS.

FOLDING COT.

1,285,790.

Specification of Letters Patent.

Patented Nov. 26, 1918.

Application filed October 7, 1916. Serial No. 124,215.

To all whom it may concern:

Be it known that I, ISAAC S. PURCELL, citizen of the United States, residing at Oak Park, Chicago, in the county of Cook and 5 State of Illinois, have invented certain new and useful Improvements in Folding Cots; and I do hereby declare the following to be a full, clear, and exact description of the invention, such as will enable others skilled 10 in the art to which it appertains to make and use the same.

My invention relates to folding cots, and its general objects include the providing of 15 a cot which may readily be compacted into a quite small space for storage or carrying, which may be divided into two or three portions for separate transportation, which will permit of an easy and effective adjustment of the tension of the fabric, which can be 20 easily folded either wholly or in part, which will be unusually strong and rigid when erected, and which will require no tools either for its complete assembling or erection or for the tensioning or adjusting of the 25 fabric.

While cots have long been used in types in which the bed fabric remains stretched in the frame while the legs are folded with respect to the frame, or in which the fabric is 30 doubled upon itself during a folding of the frame, such types when thus folded are still too bulky for being transported conveniently on automobiles, motorcycles or the like where the space for carrying baggage is limited. Moreover, these flat-folding cots are 35 usually too heavy to permit of their being lifted by a single person, and in many cases are too bulky even for storage in the closets of apartments where a cot may be desired 40 for accommodating a guest. In my present invention I have aimed to produce a cot which might be economically built with a frame composed chiefly either of metal or of wood, and which would be unusually firm 45 when unfolded, but which would not require tools either for erecting it or for compacting it. Another object has been that of producing a foldable cot which could readily be separated into several parts, so that each 50 part could be carried on a separate motorcycle, or stored separately.

Still other objects will appear from the following specification and from the accompanying drawings, in which—

55 Figure 1 is a plan view of a cot embodying

my invention and having a metal frame, a portion of the canvas or fabric being cut away to show the intermediary stiffener and the bracing for the same.

Fig. 2 is a side elevation of the cot of 60 Fig. 1.

Fig. 3 is an enlarged fragmentary section, similar to the right hand portion of Fig. 2.

Fig. 4 is a similarly enlarged view of the 65 left hand portion of Fig. 2.

Fig. 5 is an enlarged view of the upper 70 right hand portion of Fig. 1, partly in section.

Fig. 6 is a perspective view of one of the intermediate legs and of a portion of the 75 intermediate spreader.

Fig. 7 is a perspective view of the lower 80 end of one of the legs.

Fig. 8 is a perspective view of a portion of the detachable end rail and of the fabric attached to the same.

Fig. 9 is a fragmentary view showing the 85 cot partly folded after the spreader has been detached.

Fig. 10 is a fragmentary vertical trans- 90 verse section through the cot, showing the connection and bracing of the spreader to the intermediate legs.

Fig. 11 is a diagrammatic view showing 95 the arrangement of the cot parts when the cot is erected, but with the fabric still detached from the foot of the cot.

Fig. 12 shows the ends of the interlocking 100 side rail and foot rail portions of a cot embodying my invention and in which the rails are made of wood.

Fig. 13 is a fragmentary view showing an 105 end of a steel foot rail adapted to adjust the canvas by one-half rotations.

While the component parts of the cot of 110 my invention may be constructed with substantially equal facility of various materials, there are advantages in using angle-sectioned steel (or so-called "angle iron") for most of the frame portions and in using a heavy canvas for the bed fabric, hence 115 my illustrating chiefly a construction embodying these materials. For example, in Figs. 1 to 7 inclusive, the main frame of the cot consists of a head rail 1 of a double-webbed angle iron (or channel iron) connected at one end by an elbow hinge 2 and at its other end by an offset elbow hinge 3 to the two side rails, each of the latter rails comprising a long portion 4 secured to the 110

adjacent elbow hinge and a shorter end portion 5 connected to the portion 4 by a hinge 7. Spanning the free ends or tips of the portions 5 of these side rails and slidably 5 interlocked with the said tips is a foot rail, which is desirably made of a strip of channel steel 6 housing a wooden filler block 9, and which has elements coöperating with parts of the side rail portions 5 to limit the 10 sliding of the foot rail on the side rail. For example, the back of the channel steel may be continued beyond the side webs and bent over (as in Fig. 8) to form a chamber 8 between the bent over tip and the end of the 15 wooden filler 9, into which chamber the tip of the rail portion 5 will slide and in which the latter will abut against the back of the channel steel. Or, the extreme tip of the foot rail may be bent up from one side web 20 of the channel, leaving the said chamber 8 open at both ends as in Fig. 12 in which case projections 9' on the side rail portion 5 will limit the sliding of the foot rail upon the side rails. Or, both such projections and 25 the abutting of the portion 5 against the channel web may be used, as in Fig. 1.

For the bed bottom of the cot, I preferably use a flexible fabric of a kind that will readily permit of rolling the same, as for 30 example a canvas 10. This may be secured at the head of the cot to a filler rod 11 of wood around which the end of the canvas is wrapped and which is held within the channel of the head rail 1 by rivets. The other 35 end of the cot desirably is likewise fastened to the wood filler 7 and partly wrapped around the latter. In erecting the cot, the frame is set up and the canvas (which is continuously attached to the head rail) is 40 then swung over the top of the cot while the short foot section of the frame is raised somewhat, as shown in dotted lines in Fig. 2. Then the foot rail (which is fastened to the free end of the canvas) is rotated so as 45 to wind enough of the canvas on it to leave room for slipping the ends of the foot rail into their interlocking engagement with the side rail portions 5. Then upon depressing the last named portions to bring them into 50 their normal alinement with the rail portions 4, the canvas is drawn up taut, after which the said side rail portions may be kept in alinement by hooks 12 and 13 pivoted respectively to these rail portions and 55 engaging pins on legs 14, each of which legs is pivoted to the rail portion 4 at or near the juncture of the latter with the portion 5.

The head legs 15, which are pivoted to the side rail portions 4, are likewise locked in 60 rigid positions by braces 16 and 17 extending respectively to the said portions 4 and to the head rail 1 each of said braces being pivoted at one end and having a manually detachable hook at its other end engaging 65 a suitably disposed pin. Then, to keep the

intermediate legs 14 from spreading apart, I preferably connect them by a spreader 18 disposed at a considerable distance below the side rails (so as to clear the canvas when this sags under the weight of one or more 70 persons on the cot), this spreader being likewise locked in position by braces 19 connecting the spreader and the legs 14, the braces 19 being each pivoted at one end and equipped with hooks at their other ends. 75 For cheap and effective construction, I preferably make the spreader 18 of angle steel as shown in Figs. 6 and 10 and equip it at each end with a slotted hook formation formed by slotting the longer, turned over, 80 end 20 of the angle steel. To prevent a tipping of the cot by downward pressure on its foot end (as for example, by having some one seat himself on this end) I preferably provide an auxiliary pair of legs 21 pivoted 85 to the side rail portions 5 by pivots placed at one side of the channel steel constituting such legs, so that the upper end of the legs will abut against the horizontal web of the rail portion 5 when the leg is swung out (as 90 in Fig. 2) to limit the pulling out of this leg.

While the different parts of my cot may be variously proportioned, I preferably make the main side rail portions 4 somewhat shorter than the head rail 1, so that both of 95 these side rail portions (together with the portions 5 folded back upon them) may be swung close to the head rail, as indicated in Fig. 9, in doing which the offsetting of the elbow hinge 3 permits one side rail to nest 100 between the other side rail and the head rail. Thus, in disassembling the cot, the braces holding the side rails rigid with respect to the intermediate legs are unlatched and folded close to the members upon which 105 they are pivoted, and the foot end portion of the cot is swung up. This permits the foot rail to be detached from the side rails and swung clear over the head of the bed, getting the canvas or fabric off the frame of the cot, after which the stiffener or spreader 18 is unhooked from the intermediate legs. Then, after also unlatching the braces connecting the legs at the head of the cot with 110 adjacent frame elements, the frame may be 115 folded as indicated in Fig. 7, leaving the foot rail attached to the fabric and the spreader 18 entirely separate. After this, the spreader 18 may be laid alongside the folded frame and the latter may easily be 120 rolled up in the fabric, leaving the latter to form a housing for the metal parts.

Or, if the cot is to be carried on a motorcycle or in canoes, one side rail and the legs and braces connected thereto may be detached from the rest of the frame by removing the bolt 21 of Fig. 9. Then this detached part, together with the spreader 18 may be carried separately from the balance 125 of the cot and may desirably be rolled up 130

with the tent if one is used in connection with the cot, as for example with the tent of my Patent No. 1,255,224, granted to me February 8, 1918.

5 However, while I have illustrated and described a desirable embodiment of my invention, I do not wish to be limited to the various details of the construction and arrangement as here disclosed, since the same 10 might be modified in many ways without departing from the spirit of my invention. For example, it will be evident that wooden rails might be used in place of the angle steel side rails, and likewise in place of both 15 the channel steel end rails and the wood fillers associated with the latter. In that event, the wooden side and end rail portions at the foot of the cot may be suitably interlocked by using castings on some of them, as 20 for example the forked casting of Fig. 12. In either case, it will be obvious that a partial rotation of the foot rail before interlocking it with the side rails will either loosen or tighten the bed fabric, thus readily permitting 25 the latter to be adjusted to a desirable tension. The angle steel legs of my cot are each equipped with a foot 22 formed from one flange of the leg. Moreover, it should be understood that the various novel

features of my invention may be employed 30 either singly or in any desired combinations.

I claim as my invention:

1. A folding cot comprising a head rail, side rails each including a head section hinged to the head rail and folding thereupon and a foot section hinged to the head section and folding thereupon, a foot rail detachably secured to the foot sections of the side rail, and supporting legs hinged to and foldable upon the head and foot sections of the side rails respectively. 35

2. A folding cot comprising a head rail, side rails each including a head section hinged to the head rail and folding thereupon and a foot section hinged to the head 40 section and folding thereupon, the hinge axis between the head rail and head section being at right angles to the hinge axis between the head and foot sections of the side rails, a foot rail detachably secured to the 45 foot sections of the side rails, and supporting legs hinged to and foldable upon the head and foot sections of the side rails respectively. 50

Signed at Chicago, Illinois, October 3rd, 55 1916.

ISAAC S. PURCELL.
